LOUIS GUTMAN AND BENJAMIN GUTMAN, OF NEW YORK, N. Y.

PETTICOAT.

1,210,466.

Specification of Letters Patent. Patented Jan. 2, 1917.

Application filed August 15, 1916. Serial No. 114,959.

To all whom it may concern:

Be it known that we, LOUIS GUTMAN and BENJAMIN GUTMAN, citizens of the United States, and both residents of the borough of Manhattan, in the city, county, and State of New York, have invented a certain new and useful Improvement in Petticoats, of which the following is a specification.

This invention relates to petticoats having self-adjusting waistbands, and the object is to provide a skirt of this character which fits and hangs in a superior manner. Skirts are known wherein the waistband has an inextensible front and an elastic back, but such waistbands are not conforming over the abdomen and will not always stay in place in front. We have discovered that the elasticity can be more advantageously distributed between the front and back of the garment, though more in the back than in the front, and particularly when the elastic of the front section is subjected to relatively slight initial tension, so that the puckers of this section tend to disappear when the garment is worn, thereby insuring the desired smoothness of front while securing a better fit and overcoming any tendency to slip.

In the accompanying drawings illustrating the invention: Figure 1 is a fragmentary side elevation showing the petticoat being worn; and Fig. 2 is an enlarged top perspective of the skirt, a part of the waistband at the back being broken away to reveal the elastic within.

The petticoat has its placket 2 at or toward one side, and front and back elastic sections 3 and 4 in its waistband. These elastic sections may be formed in a known manner by inserting lengths of elastic 5 between the walls of the waistband and sewing them to the material throughout their length by lines of stitching 6, this sewing being performed while the elastics are stretched, so that when the sewing is completed and the elastics released these sections of the waist-

band are drawn into small puckers, as shown in the drawings.

It will be observed that the rear elastic section occupies only a portion of the back, 50 and that the front section is materially the shorter of the two. Furthermore, we prefer to make the front section with proportionately fewer or less pronounced puckers than the back section, this being accomplished by straining the front elastic to a much less degree than the rear one when the garment is made. In this way when the waistband is stretched, as when being worn, 60 the slight fullness at the front will be taken out or approximately removed, while fullness still remains at the back, thereby securing the advantages already indicated.

While we have described the invention with particular reference to petticoats, it 65 will be understood that the waist-band of the invention may be embodied in women's skirts and underwear wherever it may be useful.

What we claim as new is:

1. A petticoat having a waistband provided with a side placket and with an elastic section in the back and another elastic section in front, the front elastic section being materially shorter than the back section and 75 being self conforming and retaining over the abdomen while the back section affords adjustability as to size.

2. A petticoat having a waistband comprising separate elastics inserted in the back 80 and in the front, said elastics being united to these portions of the waistband while stretched, and normally holding these portions in a puckered condition, the front elastic, however, being initially stretched 85 substantially less than the back elastic, so that the puckering in front is slight as compared with that in the rear and tends to disappear when the garment is worn.

LOUIS GUTMAN.
BENJAMIN GUTMAN.
